DESIGN FOR A CENTRIFUGAL BLOWER WHEEL

Addison W. Evans, Torrington, Conn., assignor to
The Torrington Manufacturing Co., Torrington,
Conn., a corporation of Connecticut

Application May 18, 1940, Serial No. 92,451

Term of patent 14 years

To all whom it may concern:

Be it known that I, Addison W. Evans, a citizen of the United States, residing in the city of Torrington, county of Litchfield, and State of Connecticut, have invented a new, original, and ornamental Design for a Centrifugal Blower Wheel, of which the following is a specification, reference being had to the accompanying drawing, forming a part thereof.

In the drawing: Fig. 1 is an end elevation of a centrifugal blower wheel, embodying my design; Fig. 2 is a side elevation of the wheel shown by Fig. 1; Fig. 3 is an end elevation of the wheel,

viewed from the end opposite that shown by Fig. 1; Fig. 4 is a sectional view as taken along line 4—4 of Fig. 1, and Fig. 5 is a sectional view as taken along line 5—5 of Fig. 1.

The dominant features of my design reside in a centrifugal blower wheel provided with a plate at one end thereof having a web and annular depressed portions thereon of the configuration shown.

I claim:

The ornamental design for a centrifugal blower wheel, substantially as shown and described.

ADDISON W. EVANS.
